US00D995468S

(12) **United States Design Patent** (10) **Patent No.:** **US D995,468 S**
(45) **Date of Patent:** **** Aug. 15, 2023**

(54) **EARPIECE**

(71) Applicant: **SHENZHEN SHOKZ CO., LTD.**,
Guangdong (CN)

(72) Inventors: **Haofeng Zhang**, Guangdong (CN);
Yongjian Li, Guangdong (CN); **Lei Zhang**, Guangdong (CN); **Lei Tang**, Guangdong (CN); **Zeying Zheng**, Guangdong (CN); **Yunbin Chen**, Guangdong (CN)

(73) Assignee: **SHENZHEN SHOKZ CO., LTD.**,
Shenzhen (CN)

(**) Term: **15 Years**

(21) Appl. No.: **29/784,599**

(22) Filed: **May 20, 2021**

Related U.S. Application Data

(63) Continuation of application No. 29/781,986, filed on May 3, 2021.

(30) **Foreign Application Priority Data**

Nov. 20, 2020 (CN) 202030709008.1

CLAIM

The ornamental design for an earpiece, as shown and described.

DESCRIPTION

FIG. 1 is a back, top, and left side perspective view of an earpiece showing the new design;

FIG. 2 is a perspective view thereof;

FIG. 3 is a top view thereof;

FIG. 4 is a bottom view thereof;

FIG. 5 is a right side elevational view thereof;

FIG. 6 is a left side elevational view thereof;

FIG. 7 is a rear elevational view thereof; and,

FIG. 8 is a front elevational view thereof.

(Continued)

The broken lines depict portions of the earpiece that forms no part of the claimed design.

1 Claim, 7 Drawing Sheets
